PERMANENT LOOSE LEAF BINDER

Jay Raymond Newland and Joseph J. Polderman, Kalamazoo, Mich., assignors to Remington Rand Inc., Buffalo, N. Y.

Application October 16, 1931, Serial No. 569,334

6 Claims. (Cl. 85—4)

This invention relates to binders of the loose leaf type and it has particular relation to a permanent locking device for binding bodies of loose leaf sheets.

5 It has been customary in maintaining records in loose leaf binders to provide various kinds of temporary locking devices to prevent accidental displacement of a body of loose leaf record sheets or of the individual record sheets. As a record 10 system progresses it is desirable at certain stages of development to preserve the records in volumes of the loose leaf type. On the other hand, it is often desirable to assemble permanent loose leaf blank books. Although the previously known 15 types of binders which are disassembled at will, and could be employed for this purpose, it is apparent that the removable character of the sheets may result in displacement, loss, or other inconvenience.

20 According to one embodiment of the invention a binder of the loose leaf type has been provided which may be built up into any size of volume and which can be permanently bound in a very simple and efficient manner. One form of the 25 construction embodying the invention includes binding posts upon which the record sheets are assembled, and cover sections which are clamped together by manipulating parts of the binding posts. Permanent securing devices may be in 30 the form of dogs which are adapted to be struck with a suitable tool for engaging or anchoring them, or inaccessible clutching mechanism may be employed in telescoping parts of cover clamping devices.

35 For a better understanding of the invention reference may now be had to the accompanying drawings, forming a part of this specification, of which

40 Fig. 1 is a perspective of a binder of the loose leaf type in which a body of loose leaf sheets are permanently bound according to the invention;

Fig. 2 is a fragmentary cross section, on a larger scale, taken through one of the clamping members of the construction shown by Fig. 1;

Fig. 3 is a cross section, on a larger scale, taken substantially along the line III—III of Fig. 2;

Fig. 4 is an exploded perspective of a locking device;

50 Fig. 5 is a cross section of another form of locking device;

Fig. 6 is a cross section, on a larger scale, taken substantially along the line VI—VI of Fig. 5;

Fig. 7 is a vertical section taken substantially 55 along the line VII—VII of Fig. 6;

Fig. 8 is a vertical section of another form of locking device;

Fig. 9 is a cross section, on a larger scale, taken substantially along the line IX—IX of Fig. 8; and

Fig. 10 is a perspective of one of the locking elements included in the construction shown by Fig. 8.

Referring to Figs. 1 to 4, the invention is incorporated in a loose leaf type of binder 20 having cover sections 22 and hinging portions 23, and including binding members 24. A plurality of binding posts or clamping devices 26 are inserted through openings 27 in the binding members 24 and through openings 28 in a body of loose leaf sheets 29.

Each locking device comprises an assembling section 30 having an axial opening 32 therein and a head 33 at one end thereof. The loose leaf sheets are assembled upon these sections 30 before they are permanently clamped together. Each of these sections is adapted to receive in telescoping relation in its opening 32 a cooperating section 34 in the form of a pin having an axial opening 36 therein which communicates 25 with a radially disposed slot or recess 37 extending along one side thereof. One wall, that is, the bottom of the slot is inclined outwardly, as indicated at 38, toward one end of the section and a head 39 is formed at the other end thereof. 30

After the body of sheets 29 has been built up upon the sections 30 to a thickness equal approximately to the thickness of the body of sheets 29 shown by Fig. 2, and it is desired to clamp them together permanently, a dog 40 having one side 35 formed with teeth 42 is inserted into each of the slots 37 in such manner that the teeth project outwardly. Then the pin section 34, together with the dog, is inserted into the opening 32 of the tubular section 30. One side of the dog engages the inclined wall 38 of the slot and the opposite side having the teeth 42 thereon contacts the surface of the wall defining the opening 32.

An anchoring pin 43 in the form of a nail, having a blunt end, or the like, is then inserted 45 in the opening 36 and driven against the dog by means of a suitable tool thereby wedging the dog tightly between the wall of the opening 32 and the inclined portion 38 of the wall. Thus the teeth 42 bite into the wall of the opening 32. 50 Therefore, any force tending to withdraw the section 34 from the section 30 wedges the dog progressively tighter and the sections are thereby firmly and permanently secured together. The heads of the sections engage the outer sur- 55

faces of the clamping members 24 of the cover sections and accordingly the entire binder is permanently assembled in compact and neat form. The pin 43 is withdrawn and employed 5 for locking other sections in the same manner.

In the form of the invention shown by Figs. 5 to 7 a locking device 44 which is adapted to clamp the binder in the same manner as that described with reference to Figs. 1 to 4 is composed of interfitting sections 46 and 47, the latter of which is tubular in form and is provided with a head 48 at one end thereof. The other section is provided with a head 49 at one end and includes a stem 50 screw threaded axially into the main body 15 portion of the section. An intermediate cylindrical portion 52 of the stem is smaller in diameter than the body portion of the section and abuts against the end thereof. A conical surface 53 adjacent the end of the stem increases in diameter 20 toward the end until it is almost as large as the internal diameter of the tubular section 47. A collar 54 surrounding the intermediate portion 52 has a flared mouth surface 56 corresponding approximately to the configuration of the conical surface 53 and a plurality of balls 57 are rotatably disposed within recesses 58 in the collar in such relation that portions of the ball extend outwardly beyond the outer surface of the collar and other portions thereof extend inwardly 25 beyond the internal surface of the collar at the beginning of the flared mouth surface 56. One end of a coil spring 59 that surrounds the intermediate portion 52 and is under compression rests upon the end of the collar 54 and normally urges 30 the balls in wedging relation between the inner surface of the tubular section and the conical surface 53, whereas the other end of the spring rests against the end of the body portion of the section 46. From this construction it will be apparent 35 that the section 46 can be inserted and pressed into the tubular section 47 and that the clutching of the balls 57 against the conical surface 53 and the inner surface of the tubular section prevents disassembly of the device 44.

45 Referring to Figs. 8 to 10 a clamping device 60 is shown which comprises a tubular section 62 having a head 63 at one end and is open at the other end to receive therein a pin section 64 having a slot 66 extending from its head 67 toward its 50 other extremity. The inner wall of the pin defining the slot is curved, as indicated at 68, and the sections 62 and 64 are assembled by telescoping them and then inserting in the slot 66 an elongate dog 69 having teeth or serrations 70 at one end 55 thereof that normally face outwardly toward the inner surface of the tubular section 63. The dog is inserted through the slot 66 which extends through the head 67 of the pin. After the binder with the loose leaf sheets therein is assembled 60 upon the section 62, the section 63 is inserted therein and the dog 69 is then driven inwardly until the teeth bite into the inner surface of the section 62 as the dog rides outwardly upon the inclined wall portion 68. The dog is driven in 65 this manner until its outer end is flush with the head 69 of the section 63.

From the foregoing description it will be apparent 70 that the several designs of securing devices embodying the invention are particularly adapted to be employed in loose leaf binders to provide neat and permanent records, the parts of which cannot be accidentally disassembled or displaced and such records are insured against undesirable 75 tampering by irresponsible persons.

Although several forms of the invention have been shown and described in detail it will be apparent to those skilled in the art that the invention is not so limited but that various changes may be made therein without departing from the 5 spirit of the invention or from the scope of the appended claims.

We claim:

1. A permanent binding post for a loose leaf binder, comprising slidably interfitting members 10 for permanently binding a set of sheets between a pair of covers, one of said members being a headed hollow member extending through one of the covers, and the other member being a second headed member having an elongated recess of 15 varying depth in one side thereof extending through the other cover and disposed in the hollow member, a wedging device movable in the recess between said members and engaging the inner surface of the hollow member, and means 20 in the recess and between said members for permanently securing the wedging device in wedged position between the members in the recess against the inner surface of the hollow member to provide a permanent binder for the body of 25 record sheets.

2. A permanent binding post for a loose leaf binder, comprising slidably interfitting members for permanently binding a set of sheets between a 30 pair of covers, one of said members being formed to provide a tubular assembling device for receiving the sheets and extending through one of the cover sections, the other of said members being formed to provide a headed pin section extending 35 through the other cover section and into said assembling device, said pin section having a recess of varying depth in one side, a dog loosely disposed in said recess, and means for insertion into said recess for engaging and forcing the dog 40 into wedging relation between the pin section and the assembling device.

3. A permanent binding post for a loose leaf binder, comprising slidably interfitting members for permanently binding a set of sheets between a 45 pair of covers, one of said members being formed to provide a tubular assembling device for receiving sheets and extending through one of the cover sections, the other member providing a pin 50 section extending through the other cover section into said tubular device, said pin section having an inclined surface on one side facing the inner surface of the tubular assembling device, and a dog disposed between said inclined surface and the inner surface of the tubular device, means 55 extending between the pin section and tubular device and adapted to be forced against the dog to wedge the latter firmly between said inclined surface and the tubular assembling device whereby the cover sections are permanently secured 60 together.

4. A permanent binding post for a loose leaf binder, comprising a pair of interfitting members for permanently binding a set of sheets between a 65 pair of cover sections, one member providing a tubular assembling member extending through one of the cover sections having a cover engaging head on one end, the other member providing a one way clutching device extending through the other cover section into said tubular member and having a head on one end seating against said cover, said clutching device including a stem extending axially within the tubular member, the end portion of the stem having an inclined surface 70 thereon, a collar having a plurality of balls 75

disposed therein surrounding the stem, and means for urging the balls in wedging relation between the inclined surface and the inner surface of the tubular member.

5. A permanent binding post for a loose leaf binder, comprising a pair of interfitting members for permanently binding a set of sheets between a pair of cover sections, one member providing a tubular assembling member extending loosely through one of the cover sections, and having a head on one end to engage said cover, the other member providing a one way clutching device extending through the other cover section into said tubular member, said clutching device including a stem having a head at one end and an outer conical surface on the other end, a collar having balls disposed loosely therein surrounding the stem and a spring surrounding the stem and urging the collar toward the conical surface, whereby the tubular assembling member and the clutching device are permanently secured together.
